United States Patent Office

Des. 209,951
Patented Jan. 23, 1968

209,951

BOTTLE

David John Victor Smith, 28 Belmont Road,
Crowthorne, Berkshire, England

Filed Sept. 27, 1966, Ser. No. 4,049

Term of patent 14 years

(Cl. D9—37)

Fig. 1.

Fig. 2.

Fig. 3.

Fig. 4.

I claim:

The ornamental design for a bottle, as shown.
